United States Patent Office.

JAMES M. BARRETT, OF PLYMOUTH, NORTH CAROLINA.

Letters Patent No. 94,379, dated August 31, 1869.

IMPROVED LINIMENT.

The Schedule referred to in these Letters Patent and making part of the same.

To all whom it may concern:

Be it known that I, JAMES M. BARRETT, of Plymouth, in the county of Washington, and State of North Carolina, have invented a new and valuable Improvement in Medical Compounds; and I do hereby declare that the following is a full, clear, and exact description of the same.

My invention relates to medicines; and

It consists mainly in a novel compound of ingredients, intended to serve as an efficient remedy for sprains, scalds, burns, cutaneous eruptions, boils, and other sores, when applied as a liniment, and for various diseases when taken internally.

To compound my remedy, I take of pure whiskey or brandy, one quart; of spirits of turpentine, ten ounces; of sweet oil, ten ounces; of laudanum, four ounces; of camphor-gum, two ounces; and of opodel-

doc, four ounces, and mix them thoroughly together by any suitable means.

When thus compounded, the medicine is ready to be bottled and used.

What I claim as my invention, and desire to secure by Letters Patent, is—

The liniment or medical compound herein described, compounded of the ingredients and in the proportions herein specified.

In testimony that I claim the above, I have hereunto subscribed my name, in the presence of two witnesses.

JAMES M. BARRETT.

Witnesses:

D. C. GUTHIER,
Wm. F. HAMPTON.
